Specification of Letters Patent.

Patented July 8, 1919.

Original application filed September 17, 1917, Serial No. 191,722. Divided and this application filed November 30, 1917. Serial No. 204,487.

To all whom it may concern:

Be it known that I, THOMAS A. KEEFER, a citizen of the United States, residing at Dayton, in the county of Montgomery and 5 State of Ohio, have invented certain new and useful Improvements in Locks, of which the following is a specification, reference being had therein to the accompanying drawing.

10 This invention relates to locks for doors and other structures, and more particularly to a lock in which the bolt is actuated by a mechanism other than, but controlled by, a key, thus relieving the key of the burden 15 which is imposed upon it when it is required to move the bolt.

The object of the invention is to provide 20 a controlling device which will control the movement of the bolt actuating mechanism and will itself be controlled by the key, and 25 which will be very simple in its construction and operation; and of such a character that it can be manufactured at a low cost and will not be liable to be broken or disarranged 25 by the normal operation of the lock.

It is also an object of the invention to provide 30 a controlling device of this kind comprising but a single member which will co-operate with both the bolt actuating mechanism and with the key controlled device to control 35 the movement of the bolt actuating mechanism; and which, further, will co-operate with the key actuated device to prevent the removal of the key after the bolt operating mechanism has been released and before the bolt has been actuated.

Other objects of the invention will appear 40 as the mechanism is described in detail.

In the accompanying drawings Figure 1 40 is a sectional view taken longitudinally of a lock embodying my invention, and partly broken away; Fig. 2 is a detail view of the bolt and its actuating cam; Fig. 3 is an elevation of the escutcheon showing the controlling device in a position to lock the bolt actuating mechanism against movement; and Fig. 4 is a similar view showing the bolt actuating mechanism released.

In these drawings I have illustrated the 50 invention as applied to a recording lock such as is shown in the application for patent filed by me September 17, 1917, Serial No. 191,722, of which application the present ap-

plication is a division. It will be understood, however, that the device of the present application is useful not only in recording locks but in locks of various kinds and that the mechanism here illustrated is chosen for the purpose of illustration only.

In that form of the invention here illustrated I have shown the bolt 1 as slidably mounted in a casing 2 having a base plate 3 rigidly secured to the door, or other supporting structure. Any suitable means may be provided for actuating the bolt. In the present instance, a shaft 4 is journaled in the base plate 3 and extends through a slot 5 in the bolt. Rigidly secured to this shaft is a cam 6 which is arranged between two studs, 7, projecting from the face of the bolt and preferably provided with anti-friction rollers. The shape of the cam is such that it will in all positions be in engagement with, or will lie very close to, both studs, thus preventing the movement of the bolt independently of the cam and the shaft 4. In the present instance the shaft is designed to rotate in one direction only and the shape of the cam is such that a half rotation of the shaft will project the bolt and the next half rotation of the shaft will retract the bolt. Means are also provided to prevent the return movement of the bolt after it has been started in one direction before its movement has been completed, and to accomplish this I have here shown a ratchet wheel 8 which is secured to the shaft and engaged by a pawl 9 which permits of the rotation of the shaft in but one direction. Any suitable means may be provided for actuating the shaft, preferably it is provided at one or both ends with an operating member, such as a knob 10. In the particular lock to which the invention is applied it is desirable that the bolt should be always free to be operated from the inside of the door and I have, therefore, shown the outer portion, 11, of the shaft 4, with which the knob 10 is connected, as separated from that part of the shaft which carries the bolt actuating cam, and have provided the adjacent ends of the two parts of the shaft with co-operating clutch members, 12 and 13, which will cause the shaft as a whole to be rotated when the knob is actuated, but will permit the inner part of the shaft to be rotated to actuate the bolt when the outer and

90

85

75

70

65

60

55

inner part are locked against movement. The knob 10 may be secured to the shaft in any suitable manner, but in the present construction it is shown as journaled in an 5 escutcheon 14 which is secured to the outer side of the door and is provided with a longitudinal bore to receive the end of the part 11 of the shaft. The shaft is so connected with the knob as to cause it to rotate there- 10 with and in the present construction this is accomplished by providing the part 11 of the shaft with a longitudinal slot 15 which opens through the outer end of the shaft and is adapted to receive a pin 16 mounted in the 15 trunnion of the knob and extending trans- versely of the bore thereof.

A spring 17 confined between the inner end of the trunnion of the knob and the clutch collar 12 serves to hold this part of 20 the clutch in yielding engagement with the other part 13 thereof. This construction further permits of the escutcheon being readily removed and also permits the outer portion of the shaft to be removed, if de- 25 sired, without interfering with the other portions of the mechanism. It will be under- 30 stood that the two part construction of the shaft and the manner of connecting the knob thereto are peculiar to the present embodiment of the invention and are by no means essential to its proper operation.

The locking or controlling device for the bolt actuating mechanism may be applied to the bolt, or its actuating mechanism, at any 35 suitable point, but in the present embodiment it is preferable that it should be connected with the outer part 11 of the shaft and I have, therefore, shown the controlling device as mounted within the escutcheon 14 40 and coöperating with that portion of the shaft which extends through the escutcheon. The bolt actuating device may take various forms, but in the present construction I have illustrated it as comprising a single controlling 45 member, or plate, 18, slidably mounted upon the escutcheon, and preferably secured thereto by means of screws 19 extending through slots 20 in the plate. This controlling member is provided with a part which 50 is movable into and out of locking coöperation with a part of the bolt actuating mechanism. As here illustrated a locking member, or disk, 21, is rigidly secured to the bolt operating shaft, this being preferably ac- 55 complished by pinning the same to a collar 22 which is mounted on the inner end of the trunnion of the knob 10 and is secured to that trunnion by the pin 16, which also ex- 60 tends through the slot in the outer part 11 of the shaft, thus tying together the knob, the shaft, and the disk. This disk is pro- 65 vided with one or more notches, 23, there being, in the present instance, two of these notches arranged in diametrically opposite portions of the disk, to receive a part car-

ried by the controlling member, such as an integral lug 24 projecting from the upper end thereof. The controlling member 18 is preferably spring actuated to cause it to be held normally in engagement with the disk 70 21 when the bolt actuating devices are in their normal, or home, positions, and as here shown a spring 25 is connected at one end with the plate and at its other end with a pin 26 secured to the escutcheon and extending through a longitudinal slot, or opening, 27, formed in the controlling member 18.

A suitable key actuated device is provided to move the controlling member, against the tension of the spring, into an inoperative 80 position, thereby releasing the bolt actuating mechanism and permitting the same to be operated. This device may take various forms and will probably be modified to accommodate it to the various types of locks 85 to which the invention is applied. In the present construction I have employed a cylinder lock of a well known type, which comprises a rotatable key barrel 28 slotted to receive a key 29, the insertion of which actuates the tumblers to release the key barrel 90 and permit the same to be rotated by the key, and I have connected the key actuated member or device with this key barrel. As here shown this key actuated device is in 95 the form of a disk, or plate, 30, rigidly secured to the inner end of the key barrel, 100 preferably by mounting the same upon a hub or collar, 31, which in turn is secured to the key barrel. A spring 32 coiled about the hub 31 and engaging a pin 33 on the escutcheon tends to hold the key barrel normally in its home position, in which position only can the key be removed therefrom. This key actuated device and the controlling 105 member have coöperating parts so arranged that the movement of the key barrel from its normal or home position will cause the controlling member to be moved into its inoperative position, and further, the two 110 parts so coöperate that the controlling member will be retained in its inoperative position and the key barrel will be prevented from returning to its home position until the bolt has been actuated. In the present 115 arrangement of the mechanism the controlling member 18 is provided with an opening 34 arranged in alinement with the key barrel, and the disk, or plate, 30, which is carried by the key barrel, is 120 arranged within this opening and has a part adapted to bear against one end wall of the opening to actuate the controlling member. As here shown the disk 30 has a cam-shaped portion, or nose, 35, the lower 125 portion of which will, when the disk is in its normal position extend substantially parallel with the lower end wall of the opening in the controlling member. When the disk is rotated the cam-shaped portion thereof 130

will bear upon the adjacent portion of the controlling member and move the same downward a distance sufficient to disengage the lug 24 of the controlling member from the locking disk of the bolt actuating mechanism. To retain the key actuated disk in this position the lower wall of the opening 34 is provided with an offset portion which forms a shoulder 36, so arranged that when the key actuated disk has moved the controlling member to its inoperative position the cam-shaped portion, or nose, 35, thereof, will pass the shoulder 36 thus permitting the controlling member to be moved upward by its spring a distance sufficient to cause the shoulder to lie in front of the nose of the disk and thus lock the same against return movement. This upward movement of the controlling member is not, however, sufficient to cause the lug 24 thereof to assume an operative position with relation to the disk 21. The upper portion of the opening 34 in the controlling member is provided with a shoulder 37 which forms a stop arranged in the path of a projection or nose 38 carried by the key actuated disk and serves to limit the movement of this disk. When the controlling member has been moved into its inoperative position and the parts are in the position shown in Fig. 4 it will be apparent that the bolt actuating mechanism is free to be operated and that the key barrel is locked out of its normal position, so that the key cannot be removed. Means are provided for releasing the controlling member from the key actuating device and permitting the same to be moved into its operative position when the bolt actuating mechanism has completed its operative movement, thus causing the bolt operating mechanism to be automatically locked at the end of each operation. This means also serves to release the key barrel and permit the key to be removed at the completion of the operation of the bolt actuating mechanism. In the mechanism here shown these results are accomplished by providing the locking disk 21 of the bolt actuating mechanism with a cam-shaped projection, or nose, 39, arranged at the forward side of each notch 23. As the bolt operating mechanism approaches the end of its operative movement one of the cam-shaped portions of the disk will engage the lug 24 of the controlling member and move this member downwardly a distance sufficient to move the shoulder 36 out of the path of the nose 35 of the key actuated disk, and thus permit this disk to be returned to its normal position by the action of the spring 32. As soon as the movement of the bolt actuating mechanism has carried the cam-shaped portion of the locking disk 21 past the lug 24 the spring 25 will move the locking member upwardly and the lug

24 will be moved into the notch in the disk 21, thus again locking the shaft 11 against rotation.

The operation of the mechanism has been fully described in connection with the description of the several parts thereof and it will be apparent that I have provided a lock controlling device which is very simple in its construction and operation and which will positively control the movements of both the bolt actuating mechanism and the key; and further, that the device is highly efficient in operation and easy of maintenance as it has no part which will be easily broken or disarranged in the normal operation of the lock.

I wish it to be understood that I do not desire to be limited to the details of construction as various modifications thereof will occur to a person skilled in the art.

Having now fully described my invention, what I claim as new and desire to secure by Letters Patent, is:—

1. In a lock, bolt actuating mechanism, a controlling device movable into and out of a position to lock said mechanism against operative movement, a key actuated device to move said controlling device into an inoperative position, and means to automatically return said controlling device to its operative position.

2. In a lock, bolt actuating mechanism, a controlling device movable into and out of a position to lock said mechanism against operative movement, a key actuated device to move said controlling device into an inoperative position and to retain the same in that position, and means controlled by said actuating means to release said controlling device and permit it to return to its operative position.

3. In a lock, a bolt, a controlling device movable into and out of a position to prevent said bolt from being operated, a key actuated device having a portion to engage said controlling device, move the same into and retain the same in an inoperative position, and means other than said key actuated device to release said controlling device from said key actuated device.

4. In a lock, bolt actuating mechanism, a controlling device movable into and out of a position to lock said mechanism against operative movement, a key actuated device having a cam-shaped portion to engage said controlling device and move the same into an inoperative position, and to retain said controlling device in said position, said actuating mechanism having means to release said controlling device from said key actuated device.

5. In a lock, bolt actuating mechanism, a controlling device movable into and out of a position to lock said mechanism against operative movement, a key actuated device

to move said controlling device into an inoperative position, said controlling device and said key actuated device having parts coöperating to retain them in the positions 5 to which they have been moved, and said actuating mechanism having means for disconnecting said parts to permit them to return to their normal positions.

6. In a lock, bolt actuating mechanism, a 10 controlling device movable into and out of a position to lock said mechanism against operative movement, a key actuated device to move said controlling device into an inoperative position, said controlling device having means to prevent the return of said key actuated device to its normal position, and said bolt actuating mechanism having means to release said key actuated device from said controlling device.

20 7. In a lock, bolt actuating mechanism, a controlling device movable into and out of a position to lock said mechanism against operative movement, a spring to hold said device normally in locking relation to said 25 mechanism, a key actuated device to move said controlling device against the tension of said spring, said devices having coöperating parts to hold them in the positions to which they have been moved, and means 30 actuated by said bolt operating mechanism to disconnect said parts and permit said devices to return to their normal positions.

8. In a lock, bolt actuating mechanism, a controlling device movable into and out of a 35 position to lock said mechanism against operative movement, a key actuated device to move said controlling device to an inoperative position, a spring tending to move said key actuated device to its normal 40 position, said controlling device having a shoulder adapted to engage said key actuated device and prevent the same from returning to its normal position, and means actuated by said bolt actuating mechanism to move 45 said shoulder out of the path of said key actuated device to permit the latter to return to its normal position.

9. In a lock, bolt actuating mechanism, a controlling device movable into and out of a 50 position to lock said mechanism against operative movement, a spring tending to move said controlling device toward its operative position, a key actuated device to move said controlling device into an inoperative 55 position, said controlling device having a part arranged to be moved into the path of said key actuated device when said controlling device has been moved to its inoperative position, and means actuated by 60 said bolt actuating mechanism to move said part of said controlling device into an inoperative position to permit said key actuated device to return to its normal position.

10. In a lock, a bolt actuating mechanism 65 comprising a disk having a notch, a con-

trolling device having a part adapted to enter the notch in said disk, a spring tending to move said part of said controlling device toward said notch, a key actuated device having a cam-shaped portion arranged 70 to engage said controlling device to move the same away from said disk, said controlling device having a part arranged to be moved into the path of said key actuated device when said controlling device has been 75 moved into an inoperative position, and a spring tending to move said key actuated device toward its normal position, that part of said controlling device which enters the notch in said disk being arranged to be engaged by a part carried by said disk to impart movement to said controlling device to disengage the same from the cam-shaped portion of said key actuated device to permit the latter to be returned to its 80 normal position.

11. In a lock, bolt actuating mechanism, a controlling device comprising a single member movable into and out of a position to lock said mechanism against operative movement, a key actuated device to move said controlling member into an inoperative position, and means for automatically return said controlling member to its operative position.

95 12. In a lock, bolt actuating mechanism, a controlling device comprising a single member movable into and out of a position to lock said mechanism against operative movement, a spring tending to move said member toward its operative position, a key actuated device having a cam-shaped portion arranged to engage said controlling member to move the same into an inoperative position, said key actuated device and 100 said controlling member having coöperating parts to retain them in the positions to which they have been moved, and said bolt actuating mechanism having means to actuate said member to disconnect the same 105 from said key actuated device.

13. In a lock, a bolt, a controlling device movable into and out of a position to prevent said bolt from being operated, said controlling device comprising a part having an 110 opening therein, a key actuated device having a part adapted to enter the opening in said controlling device and move said controlling device into and retain the same in an inoperative position, and means other than 115 said key actuated device to release said controlling device from said key actuated device.

120 14. In a lock, a bolt actuating mechanism, a controlling device having a part movable 125 into and out of a position to lock said mechanism against operative movement, and comprising a part having an opening therein, a key actuated device having a part adapted to enter said opening to move said 130

controlling device into and retain the same in an inoperative position, and means actuated by said bolt actuating mechanism to release said controlling device from said 5 key actuated device.

15. In a lock, bolt actuating mechanism, a controlling device having a part movable into and out of a position to lock said mechanism against operative movement, and comprising 10 a part having an opening therein, a key actuated device mounted within said opening and having a part arranged to engage one edge thereof and move said controlling device into an inoperative position, 15 said key actuated device and said controlling device having coöperating parts to retain both devices in the positions to which they have been moved, and means actuated by said bolt actuating mechanism to disengage 20 said parts of said devices and permit said devices to return to their normal positions.

16. In a lock, bolt actuating mechanism comprising a rotary member having a notch 25 therein, a controlling member mounted for reciprocatory movement toward and from said rotary member and having a part adapted to enter said notch, and also having an opening therein, a spring tending to move 30 said controlling member toward said rotary member, a key actuated device arranged within the opening in said controlling member and having a cam-shaped portion to engage the edge of said opening and move said 35 controlling member against the tension of said spring.

17. In a lock, bolt actuating mechanism comprising a rotary member having a notch therein, a controlling member mounted for reciprocatory movement toward and from 40 said rotary member and having a part adapted to enter said notch, and also having an opening therein, a spring tending to move said controlling member toward said rotary member, a key actuated device arranged within the opening in said controlling member and having a cam-shaped portion to engage the edge of said opening and move said 45 controlling member against the tension of said spring, said edge of said opening having a shoulder adapted to be moved into engagement with the cam-shaped portion of said key actuated device when the latter has been actuated to move said controlling member 50 into an inoperative position, and a part carried by said rotary member of said bolt actuating mechanism to impart movement to said controlling member to move said shoulder out of the path of the cam-shaped portion 55 of said key actuated device.

18. In a lock, bolt actuating mechanism comprising a rotary member having a notch therein, a controlling member mounted for reciprocatory movement toward and from 60 said rotary member and having a part

adapted to enter said notch, and also having an opening therein, a spring tending to move said controlling member toward said rotary member, a key actuated device arranged within the opening in said controlling member and having a cam-shaped portion to engage the edge of said opening and move said controlling member against the tension of said spring, said edge of said opening having a shoulder adapted to be moved into engagement with the cam-shaped portion of said key actuated device when the latter has been actuated to move said controlling member into an inoperative position, a part carried by said rotary member of said bolt actuating mechanism to impart movement to said controlling member to move said shoulder out of the path of the cam-shaped portion of said key actuated device, and a spring tending to move said key actuated device to its normal position. 70 75 80 85

19. In a lock, a bolt, a controlling member movable into and out of a position to hold said bolt against movement, a key barrel, an actuating device connected with said key 90 barrel and arranged to act on said controlling member to move it into an inoperative position, said controlling member and said actuating device having parts adapted to be brought into coöperating relation by the 95 movement of said actuating device to hold said controlling member in its inoperative position and to prevent the return of said key barrel to its normal position, a bolt actuating device and means controlled by 100 the movement thereof to move said part of said controlling member and the first mentioned actuating member out of coöperative relation and permit the controlling member to be moved into its operative position and 105 the key barrel to return to its normal position.

20. In a lock, a bolt actuating shaft, a disk mounted thereon and having a notch therein, a controlling member mounted for movement toward and from said disk and having a part adapted to enter the notch in said disk, a spring tending to move said controlling member toward said disk, a key actuated device having a cam-shaped portion 110 adapted to engage a part of said controlling member and move said controlling member into an inoperative position with relation to said disk when movement is imparted to said key actuated member, that part of said controlling member which is engaged by said key actuated device having a shoulder to engage the cam-like portion of said key actuated device and prevent the same from returning to its normal position, said disk 115 having means controlled by the rotation thereof to actuate said controlling member to disengage the same from said key actuated device, and means to return said key actuated device to its normal position. 120 125 130

21. In a lock, a bolt actuating shaft, a disk mounted thereon and having a notch therein, a controlling member mounted for movement toward and from said disk and 5 having a part adapted to enter the notch in said disk, a spring tending to move said controlling member toward said disk, a key barrel, a device rigidly secured to said key barrel and rotatable therewith, said device having a projection arranged to engage a part 10 of said controlling member to move the latter against the tension of the spring, said key actuated device and said controlling member having parts adapted to be brought 15 into coöperating relation when said controlling member has been moved into its inoperative position to retain said controlling member in said inoperative position and to prevent the return of said key barrel to its 20 normal position, a part carried by said disk and controlled by the rotation thereof to disengage said coöperating parts, and means to return said key barrel to its normal position and thereby release said controlling 25 member.
22. In a lock, an actuating shaft, a disk secured thereto and having a notch therein, a controlling member having a part to be moved into and out of locking engagement 30 with said notch, a spring tending to move said controlling member toward said disk, said controlling member having a bearing surface provided with a shoulder between the ends thereof, a key barrel, a plate secured to said key barrel for rotation therewith and having a cam-shaped nose, a spring tending to hold said key barrel in such a 35 position that the edge of said nose will lie substantially parallel with the bearing surface on said controlling member, said nose being so arranged that when said key barrel is rotated said controlling member will be moved against the tension of said spring until said nose and the shoulder on said 40 bearing surface are brought into interlocking engagement, and means carried by said locking disk and controlled by the rotation thereof to move said controlling member against the tension of said spring to release 45 the part carried by said key barrel and permit it to return to its normal position, thereby releasing said controlling member.
23. In a lock, a bolt actuating device, a rotatable locking disk connected with said 50 actuating device and having a notch therein, a plate mounted for lengthwise movement toward and from said disk and having a part adapted to enter said notch, a spring to move said plate toward said disk, said 55 plate having an opening therein, the lower edge of which is provided with a shoulder, a key barrel arranged adjacent to said opening, a device carried by said key barrel and having a cam-shaped nose extending into 60 said opening, a spring to hold said key barrel 65 in its normal position with said cam-shaped nose substantially parallel to the lower edge of said opening, said nose being adapted to impart lengthwise movement to said plate when said key barrel is rotated, 70 and to be brought into interlocking engagement with said shoulder whereby both parts are prevented from returning to their normal positions, and a part carried by said locking disk to impart lengthwise movement 75 to said plate and move the same out of interlocking engagement with the nose of the device carried by said key barrel to permit the same to be moved into its normal position. 80
24. In a lock, bolt actuating mechanism, a device to lock said bolt actuating mechanism against movement, a key barrel, a device to lock said key barrel against movement, and a single controlling member for said locking devices arranged to be acted upon by the locking device for said key barrel to release the bolt actuating mechanism and to be acted upon by the locking device for the bolt actuating mechanism to release the key 90 barrel. 85
25. In a device of the character described, an actuating shaft, a locking disk secured thereto, a key barrel, a locking disk secured to said key barrel, and a controlling plate to alternately engage said locking disks, said plate being arranged to be actuated by said key barrel locking disk to release said shaft, and to be actuated by said shaft locking disk to release said key 100 barrel. 95
26. In a lock, a bolt actuating mechanism, a device to lock said bolt actuating mechanism against movement, a key barrel, a device to lock said barrel against movement, and controlling mechanism to alternately engage said locking devices, said controlling mechanism being arranged to be acted upon by the locking device for said key barrel to move the same into a position to release the bolt actuating mechanism, and to be acted upon by the locking device for said bolt actuating mechanism to move the same into a position to release the key 110 barrel. 105
27. In a lock, bolt actuating mechanism comprising a rotary part having movement in one direction only and having a notch in the periphery thereof, a controlling device movable into and out of the notch in said rotary part, a key actuated device to engage said controlling device and move the same out of said notch and retain the same in its inoperative position, said rotary part having a cam shaped portion arranged in advance of said notch to engage said controlling device and release the same from said key actuated device before said notch is again brought into a position to receive said controlling member. 115
- 120
- 125
- 130

28. In a lock, bolt actuating mechanism comprising a rotary part having a plurality of notches in the periphery thereof and capable of rotation in one direction only, a 5 controlling device having a part adapted to enter one of said notches, means for retaining said part of said controlling device normally in one of said notches, a key actuated device to actuate said controlling device to 10 move said part thereof out of said notch to permit the rotation of said member, said controlling device and said key actuated device having parts coöoperating to retain them

in the positions to which they have been moved, and said rotary part having a cam-shaped portion arranged in advance of each notch to engage said controlling device and impart movement thereto for disconnecting the same from said key actuated device before the next notch therein is brought into 20 position to receive said part of said controlling device.

In testimony whereof, I affix my signature hereto.

THOMAS A. KEEFER.

Copies of this patent may be obtained for five cents each, by addressing the "Commissioner of Patents, Washington, D. C."
